UNITED STATES PATENT OFFICE.

JOSIAH WESTBROOK HURST, OF RICHMOND, ENGLAND.

ATTACHMENT TO PIANO-CASES.

1,021,525.

Specification of Letters Patent. Patented Mar. 26, 1912.

Application filed November 20, 1909. Serial No. 529,083.

To all whom it may concern:

Be it known that I, JOSIAH WESTBROOK HURST, gentleman, a subject of the King of Great Britain, residing at No. 21 Friarstile road, Richmond, in the county of Surrey, England, have invented certain new and useful Improvements in Attachments to Piano-Cases, of which the following is a specification.

13 One object of my invention is to provide a compact, convenient and ornamental cabinet attachment for pianos or similar instruments particularly designed for holding sheet music or musical records in the shape 15 of rolls. This object and other advantageous ends I attain as hereinafter set forth, reference being had to the accompanying drawings, in which:—

Figure 1 is a partial front elevation of a 20 piano illustrating my invention as applied thereto; Fig. 2, is a horizontal section on the line 2—2, Fig. 1; Fig. 3, is a vertical section on the line 3—3, Fig. 2; Figs. 4 and 25 5 are fragmentary vertical sections of modifications of my invention; Fig. 6, is a partial front elevation illustrating a form of my invention which combines the features of those forms shown in Figs. 3 and 5; Fig. 7, is a horizontal section on the line 7—7, 30 Fig. 6, Fig. 8, is a fragmentary vertical section on the line 8—8, Fig. 7, and Fig. 9, is a perspective view of one form of my invention showing the cabinet in its open position.

35 Referring to Figs. 1 to 3 of the above drawings, *a* represents a piano or similar instrument and *b* is the music cabinet or case constructed according to my invention. In this, the simplest form of the invention, 40 the cabinet is open at one side which is preferably closed by the end of the piano and is mounted upon and fastened to a base board *b*⁹ which projects for a considerable distance beyond the inner side of said cabinet and slides under the piano; the base board thereby bearing against the bottom of the piano and holding the cabinet in any given position. Casters *b*⁷ are provided 45 whereby the base board and the cabinet are supported and a handle *b*¹⁴ is mounted on the front of the cabinet as shown in Figs 1 and 2. If desired, the base board *b*⁹ may be made of heavy material such as metal 50 so as to balance the cabinet and its contents, thereby insuring its stability, and permitting it to be easily run into and out of its

closed position at will. In the upper part of the cabinet I preferably mount a number of clips or holders *b*⁴ particularly designed for the reception of music record rolls indicated at *c* in the above drawings, while in the lower portion of the cabinet I place a number of vertical partitions *b*⁵ extending from one side to the other thereof to provide compartments for sheet music indicated at *c'*.

60 In the modified form of my invention shown in Fig. 4, the top and bottom boards of the cabinet at their inner edges are provided with vertically offset studs *b*⁸ while 70 the end of the piano *a* is provided with corresponding transverse guide grooves *a*⁴ in which said studs are designed to slide; the arrangement being such that the cabinet *b* may be slid into and out of position and 75 turned on said studs as hinges in the general manner indicated in Fig. 7.

80 In the case shown in Fig. 5, the lid *a*⁵ of the piano is prolonged beyond the end of the instrument and has a groove *a*⁴ and there is a strip or step also having a groove *a*³. This step is mounted at the bottom of the piano and the cabinet is provided with vertical studs *b*⁸ designed to operate in this groove as before noted; it being possible to 85 slide the cabinet into or out of position and turn it upon its studs as pivots.

85 The features shown in the preceding figures are combined in that form of my invention shown in Figs. 6 to 9 inclusive, for 90 in this instance the base board *b*⁹ is separate from the cabinet and slides in dovetail guide strips *b*¹³ upon the piano *a*, though these may be omitted as in Figs. 1 to 3. The outer end of the base board is provided with 95 a vertical wall *b*¹⁰ as well as a top *b*¹² and a side or back *b*¹¹, thus constituting a case into and out of which the cabinet proper, indicated at *b*, is adapted to slide. The top *b*¹² and base board *b*⁹ in this case are provided with grooves *a*³ while the top and bottom of the cabinet are furnished with studs or pins *b*⁸ designed to slide in said grooves, so that, as previously described, the cabinet 100 may be drawn forward until said studs are 105 at the extremities of the grooves and thereafter turned as upon hinges, into the position shown in dotted lines in Fig. 7.

I claim:—

110 1. The combination of a musical instrument case; a base board slidable under the same; front, side and top members carried

by the base board; with a cabinet also carried by the base board in position to coöperate with said front, side and top members to form a closed container; said cabinet being free to move bodily relatively to the instrument case as well as to turn on a vertical axis.

2. The combination of a musical instrument having a case provided with members 10 projecting respectively at the upper and lower portions of one of its ends; one of the members being extended under the said case so as to be reinforced thereby and there being grooves in both of said members; with 15 a music cabinet having studs forming pivots mounted to slide loosely in said grooves, as well as to turn therein.

3. The combination of a musical instrument case; a base board slidably mounted 20 under the same and having a groove; a top piece also having a groove; and a cabinet provided with trunnions forming vertical pivots operative in said grooves and free both to turn and to slide longitudinally 25 therein.

4. The combination of a musical instrument case; a base board slidably under said case; rollers on said base board; and a cabi-

net open on one face and mounted on said base board; with means movably connecting 30 the cabinet to the base-board for guiding it from and into a position with its open face against one end of the case so as to be closed thereby.

5. The combination of a musical instrument case having supporting members projecting respectively from the upper and lower portions of one of its ends; with a cabinet having an open face; means movably connecting the cabinet to said members 40 for guiding it from and into a position with said open face against one end of the instrument case so as to be closed thereby.

6. The combination of a musical instrument case; a base board slidably mounted 45 under the same; a cabinet mounted on said base board and having an open face; with means movably connecting the cabinet to the base-board for guiding it from and into a position with said open face against the 50 end of the case; and roll supporting clips mounted in said cabinet.

JOSIAH WESTBROOK HURST.
